DESIGN FOR A TOWEL RACK

Frank Sale, Los Angeles, Calif., assignor to Gregori of Hollywood Inc., Los Angeles, Calif., a corporation of California

Application July 17, 1944, Serial No. 114,434

Term of patent 7 years

(Cl. D33—16)

To all whom it may concern:

Be it known that I, Frank Sale, a citizen of the United States residing at Los Angeles, California, have invented a new, original, and ornamental Design for a Towel Rack, of which the following is a specification, reference being had to the accompanying drawing, forming part thereof.

Referring to the drawing:

Figure 4 is a sectional view thereof in the direction of the arrows on line 4—4 of Figure 3; and

I claim:

The ornamental design for a towel rack, as shown.

FRANK SALE.
